UNITED STATES PATENT OFFICE.

WILLIAM G. RAOUL, OF SAVANNAH, GEORGIA.

CAR-AXLE BOX.

SPECIFICATION forming part of Letters Patent No. 243,620, dated June 28, 1881.

Application filed May 10, 1881. (No model.)

To all whom it may concern:

Be it known that I, WILLIAM G. RAOUL, of the city of Savannah, in the county of Chat-
ham and State of Georgia, have invented cer-
5 tain new and useful Improvements in Car-
Axle Boxes, of which the following is a speci-
fication.

This invention is designed as an improvement
upon that described in my Letters Patent No.
10 238,610, granted March 8, 1881. In that in-
vention a lid or cover hinged to the axle-box
is used in connection with a stirrup, which is
attached to the box, and swings over the lid
15 to hold it in place against the end-thrust of
the axle, which is received by a projecting boss
formed on the inner side of the lid or cover.

My present invention has for its object to
hold the stirrup firmly in place; and in its pre-
ferred form consists of a plate-steel spring,
20 which is riveted or otherwise secured to the
box lid or cover, and projects down below the
position assumed by the stirrup when locked,
which spring is provided with a notch or fric-
tional surface which interlocks with or fric-
25 tionally secures the stirrup.

In the accompanying drawings, Figure 1 is
a longitudinal section of an axle-box embrac-
ing my invention. Fig. 2 is a similar section,
30 showing the invention in a modified form.
Figs. 3 and 4 are perspective views, showing
further modifications, as hereinafter described.

Similar letters of reference indicate similar
parts in the several figures.

A is the axle-box.

35 B is the cover or lid, hung by the pivot *a* to
lugs *b b*, formed upon the box, the cover *B*
opening downward instead of upward, which
latter is the more common plan.

C is the stirrup, which is pivoted at the sides
40 of the box, and when used for locking the lid
or cover is swung to a horizontal or other suit-
able position over the cover, and thus holds
it tightly closed, the stirrup engaging the sloping
or tapering ribs *c* upon the outside of the
45 cover, as in my said prior patent.

To the outside of the lid is riveted a plate-
spring, which, as shown in Fig. 1, is provided
with a square shoulder, and in Fig. 2 with an
inclined plane or frictional surface. The elas-
50 ticity of the spring has the tendency of keep-

ing it, when not acted on by the stirrup, forced
beyond the outer limit of the sloping ribs, and
consequently when the stirrup is forced to its
closed position over said ribs it depresses the
spring until it passes over its highest point, after
55 which the spring is forced out by its own elas-
ticity, locking the stirrup either by the square
shoulder, as is seen in Fig. 1, or by the inclined
plane or frictional surface, as is shown in Fig.
2. If two ribs are used the spring is placed
60 between them, which is the construction sup-
posed in Figs. 1 and 2. If only one rib is used
one spring or one at each side of the rib may
be used, the latter construction being shown
in Fig. 3; or the spring might be forked or di-
65 vided, so as to straddle the rib, as shown in
Fig. 4. The free end of the spring extends be-
low the stirrup, so as to furnish means for
pressing it inward when it is designed to release
70 the bail.

It will be seen that this invention will effect-
ually hold the stirrup in place and prevent
its accidental displacement.

The spring, when formed with a square shoul-
der, must, of course, be depressed or pushed
75 in when it is desired to raise the stirrup; but
when the spring is used simply with an in-
clined frictional surface the stirrup may be
raised by imparting a sharp blow to it under-
neath. The inclined friction-surface has the
80 effect of continually pressing the stirrup down-
ward, and thus aids in keeping the cover or
lid to its closed position.

I claim as my invention—

1. In a car-axle box, the combination of a 85
cover or lid hinged to the end of the box, a
stirrup pivoted to the box and adapted to fit
over and hold the cover in place, and a spring-
locking device operating to secure the stirrup,
substantially as set forth.

2. In a car-axle box, the combination of a
cover or lid hinged to the end of the box and
forming a bearing to receive the end-thrust of
the axle, a stirrup pivoted to the box, and
adapted to be thrown over and secure the
95 hinged lid when closed, and a spring attach-
ment operating to lock the stirrup, substan-
tially as set forth.

3. In a car-axle box, a lid or cover hinged
to the end of the box and opening downward,
100

and a stirrup pivoted to the sides of the box and adapted to swing over and secure said lid, combined with a plate-spring device riveted to the top of the box-lid, and having a locking-surface wherewith to engage with and lock the stirrup, and a free-ended lower projection, whereby it may be depressed when it is desired to release the stirrup, substantially as set forth.

10 4. In a car-axle box, the combination of a hinged lid having sloping ribs, a pivoted stir-

rup, and a spring-locking device, the latter operating, in connection with the sloping ribs of the lid and the stirrup, to secure the lid when closed, substantially as set forth.

Witness my hand this 20th day of April, 15
A. D. 1881.

WM. GRUNE RAOUL.
